(57) **CLAIM**

The ornamental design for a table leg, as shown and described.

DESCRIPTION

FIG. 1 is a perspective view of an exemplary embodiment of a table leg;

FIG. 2 is a front view of the table leg;

FIG. 3 is a right side view of the table leg, with the left side view being a mirror image thereof;

FIG. 4 is a top view of the table leg;

FIG. 5 is a bottom view of the table leg; and,

FIG. 6 is a rear view of the table leg.

The broken lines shown in the figures are for illustrative purposes only and form no part of the claimed design.
